CLAIM

The ornamental design for a multi-functional pedometer, as shown and described.

DESCRIPTION

FIG. 1 is a perspective view of the multi-functional pedometer showing my new design;

FIG. 2 is a front elevation view thereof;

FIG. 3 is a rear elevation view thereof;

FIG. 4 is left side view thereof;

FIG. 5 is right side view thereof;

FIG. 6 is a top plan view thereof; and,

FIG. 7 is a bottom plan view thereof.
